Jacob C. Palmer, Harvey Beard, and Anthony Beard.
Saddles Patent

The Schedule referred to in these Schedules Patent and making part of the
same containing a description in the words of the said, Jacob C. Palmer
Harvey Beard and Anthony Beard, themselves of their improvement in
the spring seat of riding saddle

To All To Whom These Presents Shall Come. We it known that
we Jacob C. Palmer, Harvey Beard and Anthony Beard of the Town
of Lurayville, in the County of Augusta and State of Virginia have in-
vented a new and useful improvement in the spring seat riding saddle
and that the following is a full and exact description of the con-
struction and operation of the same as invented or improved by us. Our
improvements are applicable to any of the saddles in ordinary use and
consist in the application of springs of peculiar construction to the seat
and pommel and to the attachments of the girths or girths to the tree,
also in the construction of the head or pommel. we shall therefore con-
fine our description particularly to these parts. First in constructing
the seat spring, we form an oblong square frame of wrought iron or steel
of say $\frac{1}{4}$ inch thick and three inches and three quarters long by two inch-
es wide more or less according to the quantity of elasticity required. To the
inner side of this frame & near the end of one of its long sides is to be secured
by rivets or welding, one extremity of a zigzag or W shaped spring to be
made of tempered steel say $\frac{1}{8}$ inch thick by $\frac{1}{4}$ of an inch broad, and lapi-
ped from side to side within the frame five or more times taking care to
allow sufficient play for the action of the spring and also space enough be-
tween its loose end and the side of the frame contiguous thereto for the fringe
of the connecting straps herein after mentioned and so that the frame and
spring may lie in the same plane, a proper degree of curvature is then given
to them to conform them to the gullet of the saddle or tree. Strong straps
of leather being now passed over the loose end of the spring its ends are dou-
bled back on the latter and secured by taking in the ordinary manner of
curving.

during webbing) to the opposite side of the head of the tree, thus suspending the spring frame. We prefer also fixing an additional piece of strong webbing over the leather to be used with it, so as to form a double covering to the spring and frame which serves the two-fold purpose of protecting the horse back and of preventing the spring from corroding. We next prop a piece of strong webbing, broad as the frame will admit, over the opposite side to that which bears the spring and drawing them taught in a diverging direction attach the ends by stitching firmly to the under side of the cantle, the covering of the seat is then drawn on in the common way. Second - the girth springs are constructed precisely like that just described, the only difference being in their size, which is proportionately less and in their being perfectly flat, they are attached to the sides of the tree by straps in a similar manner. Third - the front horn, in the head of the tree which is made in the usual way. We secure an iron horn as follows. The pointed shank of the horn, which also has shoulders, is placed in between the top and gullet plates and is then bent down and clinched over the back edge of the latter, by which means it is secured firmly to the tree. The horn itself is a spoon shaped flattened piece of wrought iron, $\frac{1}{4}$ of an inch thick at the shank, and diminishing regularly to $\frac{1}{16}$ of an inch at its front edge, its breadth being about two inches at the end and one at the shank, rising from the shank with a gentle curve forward to a horizontal line, the precise figure is not deemed material and is therefore left to the fancy of the maker. This horn is first completely covered with two pieces of thick leather stitched together all around close to the plates and then the whole covered with webbing or stitching as may be preferred. Some of the advantages of our improvements are the great simplicity and cheapness of the spring and its attachments being less liable to get out of order, and by conforming neatly to the gullet of the saddle; its bulk scarcely being perceptible, at the same time making an easy elastic seat for both the horse and the rider, also its application and perfect adaptation to the girth of the saddle which by its means not only performs its office better, but with more comfort to the horse and is completely protected from injuries arising from instant

numbered operations. Also our bridle, offering great advantages over
harness made of wood, in common use, by being applicable to any tree, much
stronger and more durable and capable of being shaped or altered so as
to suit any person's hand. Also we do not claim as new in the construc-
tion of spring seat saddles, the application of a spring to the head
of the tree nor a spring of zig-zag or W shape as applied to this purpose.
But what we do claim as new, and our invention and for which
we ask Letters Patent is the form and manner of constructing the frame
and attaching the spring thereto both being curved so as to conform
to the gullet of the saddle and being attached to the tree by steeps
and webbing as herein described, we also distinctly claim the
application and use of similar springs to the girth or girths of the
saddle and also the iron horn secured and covered as herein
described and set forth. In testimony that the foregoing is a
true specification of our said improvements we have hereunto
set our hands this twenty-third day of May 1835.
